DESIGN FOR AN EMBLEM OR SIMILAR ARTICLE

Max E. Schwalbe, New York, N. Y.

Application October 12, 1934, Serial No. 53,600

Term of patent 3½ years

To all whom it may concern:

Be it known that I, Max E. Schwalbe, a citizen of the United States, residing at New York, in the county of New York and State of New York, have invented a new, original, and ornamental Design for an Emblem or Similar Article, of which the following is a specification, reference being had to the accompanying drawing, forming part thereof.

The figure is a plan view of an emblem or similar article showing my new design.

The article has no appreciable thickness.

I claim:

The ornamental design for an emblem or similar article, as shown and described.

MAX E. SCHWALBE.
